[57] CLAIM

The ornamental design for an automobile tool kit container, substantially as shown and described.

DESCRIPTION

FIG. 1 is a front elevational view of an automobile tool kit container embodying my new design.

FIG. 2 is a side elevational view taken on a plane parallel to the long side of the automobile tool kit container.

FIG. 3 is a top plan view thereof;

FIG. 4 is a left end elevational view thereof; and

FIG. 5 is a rear elevational view thereof.

FIG. 1

FIG. 2

FIG. 3

FIG. 4

FIG. 5
